UNITED STATES PATENT OFFICE.

EDWARD H. WERZNER, OF EVANSVILLE, INDIANA, ASSIGNOR TO SCHROEDER HEAD-LIGHT CO., INC., OF EVANSVILLE, INDIANA, A CORPORATION OF INDIANA.

HEADLIGHT.

1,252,065.

Specification of Letters Patent.

Patented Jan. 1, 1918.

Application filed April 17, 1917. Serial No. 162,656.

To all whom it may concern:

Be it known that I, EDWARD H. WERZNER, a citizen of the United States, and a resident of Evansville, in the county of Vanderburgh and State of Indiana, have invented a new and Improved Headlight, of which the following is a full, clear, and exact description.

This invention relates to headlights, and deals more particularly with an adjustable mounting for the lamp whereby the same can be positioned in the focal center of the reflector.

The invention has for its general objects to improve and simplify the construction and operation of devices of this character so as to be reliable and efficient in use, of durable and substantial form, and so designed that the adjustments can be easily, quickly and accurately effected.

A more specific object of the invention is the provision of a lamp mounting which is located outside the reflector and includes means whereby the lamp can be adjusted in all directions.

With such objects in view, and others which will appear as the description proceeds, the invention comprises various novel features of construction and arrangement of parts which will be set forth with particularity in the following description and claims appended hereto.

In the accompanying drawings, which illustrate certain embodiments of the invention and wherein similar characters of reference indicate corresponding parts in all the views,

Figure 1 is a fragmentary sectional view of a headlight with portions in elevation;

Fig. 2 is a plan view of the lamp and mounting with the reflector in section;

Fig. 3 is a transverse vertical section of the headlight; and

Fig. 4 is a side view of a modified form of mounting for adapting an oil headlight to an electric lamp, the reflector being shown in section.

Referring to Fig. 3 of the drawing, A designates a headlight casing of any desired construction, in the bottom of which is a horizontal slide or plate 1 which has fastened thereto a bracket 2 on which the lamp mounting B is supported. In front of the bracket 2 is a reflector 3 having an opening 4 through which extends the lamp

5. The mounting B comprises a frame 6 which is fastened by a rivet or other means 7 to the bracket 2, and on the frame is a ring 8 which borders the opening 4 and to which the reflector 3 is soldered or otherwise secured. The frame 6 has at a point to the rear of the bracket 2 a vertical socket 9 which is split to more effectively clamp a vertical stem 10, parts of the socket being provided with lugs 11 through which extends a clamping screw 12. On the upper end of the stem 10 is a horizontal socket 13 through which passes the tubular member or stem 14 which carries the socket 15 for the lamp 5. Through the tubular member 14 extend the wires 16 and 17 which connect the lamp in circuit with a source of current. The socket 13 is split so as to be resilient, and the lugs 18 at opposite sides of the split 19 have a clamping screw 20 whereby the lamp stem 14 can be adjustably held. By loosening the clamping screw 12 the socket 13, member 14 and lamp 5 can be raised or lowered or swung to the right or left in a horizontal plane, which, taken together with the longitudinal adjustment of the member 14, enables the filament of the lamp to be brought into coincidence with the focal center of the reflector.

In Fig. 4 the reflector 3a has an opening 21 at its bottom that was designed to receive an ordinary oil lamp, but instead of an oil lamp an electric lamp 22 is substituted and the mounting B' is so constructed as to enable the lamp 23 to be adjusted up or down or back or forth in a horizontal plane. The mounting B' comprises a base 23 which is fastened to the slide or plate 24, and rising from the base 23 is a frame 25 which carries a vertical split socket 26. Rotatably and vertically adjustable in this socket is a stem 27 which has on its upper end a horizontal socket 28 in which is an arm or stem 29 which is part of the head 30 that holds the lamp socket 31. The frame 25 has binding posts 32, of which only one is shown, since the other is disposed behind the one in view, and wires 33 connect the binding posts with the lamp. The lamp can be adjusted horizontally back and forth in the focal axis or swung to the right or left on the member 29 as a center, and the lamp can be raised or lowered by adjusting the stem 27 in the socket 26. It will thus be seen that it is possible to bring the filament of the

lamp in proper relation to the focal axis of the reflector.

From the foregoing description taken in connection with the accompanying drawing, 5 the advantages of the construction and method of operation will be readily understood by those skilled in the art to which the invention appertains, and while I have described the principle of operation, together 10 with the device which I now consider to be the best embodiment thereof, I desire to have it understood that the device shown is merely illustrative and that such changes may be made when desired as fall within the 15 scope of the appended claims.

Having thus described my invention, I claim as new and desire to secure by Letters Patent:

1. The combination of a reflector having 20 an enlarged opening therein, a lamp in the reflector and having a member of considerably less size than the opening of the reflector and extending through the said opening, said member carrying a stem, a split 25 bearing in which the stem is mounted to turn and slide, said bearing being provided with a stem projecting at right angles therefrom, a screw for securing the first named stem in the bearing, a support adjacent the 30 reflector and having a split bearing in which the second stem is mounted to turn and slide,

and a screw for securing the said stem in its bearing.

2. The combination of a reflector, having 35 an opening therein, a lamp in the reflector and having a member extending through and freely movable in the opening of the reflector, said member having a stem disposed parallel with the axis of the reflector, a sleeve in which the stem is slidably and rotatably mounted, said sleeve having a stem 40 projecting at right angles therefrom, means for clamping the first named stem in its sleeve, a support, to one end of which the reflector is secured, the support having at its other end a sleeve in which the stem of the 45 sleeve is rotatably and slidably mounted, and means for securing said stem in the sleeve.

3. A lamp holder of the character described, comprising a frame having at one 50 end a ring-like member to which an apertured reflector is adapted to be secured and having at its other end a vertical split socket provided with lugs in which is mounted a clamping screw, and a horizontal split 55 socket provided with lugs and in which is mounted a clamping screw, said socket being adapted to receive the stem of a lamp and having a stem extending at right angles therefrom, into the socket of the frame.

EDWARD H. WERZNER.
